UNITED STATES PATENT OFFICE.

ARTHUR E. BABCOCK, OF DOLORES, COLORADO.

SAFETY STARTING CRANK FOR INTERNAL-COMBUSTION ENGINES.

Application filed September 16, 1926. Serial No. 135,921.

This invention relates to safety starting cranks for internal combustion engines and more particularly to a device of this character which will effectually prevent injury 5 to the operator in event of a "kick" of the engine.

A further and more specific object of the invention is to provide a starting crank, the handle portion of which is so constructed 10 that it may twist and dispose itself at an angle other than the ordinary angle to the remainder of the crank, together with means whereby this twisting action serves to disconnect the handle portion of the crank 15 from the engine engaging portion thereof, when the engine is operating in a direction opposite to that in which it ordinarily operates.

A still further object of the invention is to 20 provide a starting crank for engines embodying an engine engaging portion and a hand engaged portion connected by a ratchet mechanism, the hand engaged portion being capable of a limited rotative 25 movement in its connection with the engine engaging portion and having associated therewith a cam, releasing the dogs of the ratchet mechanism, so that the handle is freed from the engine engaging portion by 30 such twisting movement.

A still further object of the invention is to so construct the handle that any tendency 35 of the engine to "kick" will naturally produce a twisting motion, which disconnects the engine and hand engaged portion of the crank.

These and other objects I attain by the construction shown in the accompanying drawings, wherein for the purpose of illustration is shown a preferred embodiment 40 of my invention and wherein:—

Figure 1 is a side elevation of a crank constructed in accordance with my invention;

Figure 2 is a sectional view through the connection between the shaft and hand engaged portions of the crank;

Figure 3 is a section at right angles to that shown in Figure 2;

Figure 4 is a section on the line 4—4 of Figure 1;

Figure 5 is a section on the line 5—5 of Figure 1;

Figure 6 is a section on the line 6—6 of Figure 1.

Referring now more particularly to the

drawings, the numeral 10 generally designates a shaft adapted at its inner end for engagement with a crank receiving element 11 of an engine. In practically all engine 60 constructions, the crank engaging element and crank have their engagement with one another in such manner that if the engine is started and operates properly, the rotation of the engine shaft 12 and the crank 65 receiving portion thereof 11 will force the crank to a disengaged position. In the present instance, the crank receiving portion is disclosed as having angular slots 13 in which a pin 14 carried by the inner end 70 of the shaft 10 engages. It will be obvious that if the engine shaft rotates in the direction of the arrow of Figure 3, the pitch of these slots will tend to retain the pin within the slots and cause the crank 10 to 75 rotate. This reverse rotation often causes injury to the operator.

In accordance with my invention, I provide the outer end of the shaft 10 with a ratchet 15 and rotatably mount upon this outer end 80 a crank including an arm 16 having pawls 17 and 18 which are spring-pressed for engagement with the teeth of the ratchet at opposite sides thereof. Upon the arm I rotatably mount a cam sleeve 19 for controlling these pawls. The end of the arm 16 is provided with a socket for the reception 85 of an extension 20 of the arm. The extension 20 is rotatable within the socket and has secured thereto a pin 21 operating 90 through a slot 22 formed in the wall of the socket. The outer end of this pin engages the cam sleeve 19, so that as the extension 20 is rotated, the cam sleeve 19 will be rotated. The rotation of the cam sleeve 19 is 95 just sufficient to disengage the pawl 17 from the ratchet. When the cam sleeve is at one limit of its movement, the pawl 17 is disengaged and when it is at the opposite limit of its movement, both pawls 17 and 18 are 100 engaged and the arm 16 is locked to the shaft 10. At the lower end of the extension 20, I provide an angular portion 23 having a rotatable hand grip 24 which, in the normal position of the extension 20, substantially 105 parallels the crank 10. When the handle is in its normal position, the shaft 10 is locked to the arm 16 and the extension 20 and in this position, the device is held while cranking the engine. If, during cranking of the 110 engine, the engine back-fires, there will be a tendency of the shaft 10 to rotate in the

direction of the arrow in Figure 3, and to carry with it the arm 16 and its extension 20. Since the hand of the operator will be engaged with the hand grip, this will offer resistance to movement of the hand grip with the result that the extension 20 will rotate upon its longitudinal axis. This rotation will shift the cam sleeve 19, disengaging the pawl 17 and permitting the shaft to rotate without obstruction from the arm 16. It is thus impossible for the engine to transmit a "kick" to the crank which will endanger the operator and the operator is enabled to retain his hold upon the crank at all times. It is, of course, obvious that the injuries, resulting from "kicks" of the engine are due to the fact that the engine imparts an impulse to the crank which tears the crank from the hand of the operator and causes the crank to swing violently around the part thereof corresponding to the shaft 10. This is, of course, absolutely avoided by use of my construction.

Since the construction hereinbefore set forth are obviously capable of a certain range of change and modification without materially departing from the spirit of the invention, I do not limit myself to such specific structure except as hereinafter claimed.

I claim:—

1. In a device of the type described, a shaft adapted at one end for engagement with the shaft of an internal combustion engine, an arm rotatably mounted upon the outer end of the shaft and provided at its free end with an angular extension affording a hand grip, means connecting the arm and shaft preventing relative rotation thereof

and means operable by pressure against the hand grip resisting rotation of the shaft from the engine in one direction for disconnecting the arm from the shaft and permitting the shaft to freely rotate in said direction.

2. In a device of the type described, a shaft adapted at one end for engagement with the shaft of an internal combustion engine, a crank ratchet connected with the opposite end of the shaft to rotate the same, said crank including a rotatable arm having a handle and means operated by movement of the handle rotating the arm in one direction, disconnecting the shaft and crank to permit rotation of the shaft with relation to the crank.

3. In a device of the type described, a shaft adapted at one end for engagement with the shaft of an internal combustion engine, a crank for rotating the shaft comprising an arm and an angular extension on said arm forming a hand grip, said arm being formed in two relatively rotatable sections one of which is rotatably engaged with the opposite end of the shaft and the other of which bears said hand grip, a ratchet mechanism connecting the shaft and the first named section of the arm including a pawl carried by the arm, a cam for disengaging said pawl to render the same inoperative and a connection between the cam and the last named section of the arm, shifting the cam to disengage the pawl when the arm is rotated.

In testimony whereof I hereunto affix my signature.

ARTHUR E. BABCOCK.
